UNITED STATES PATENT OFFICE.

HENRY C. HERR, OF DETROIT, MICHIGAN, ASSIGNOR, BY MESNE ASSIGNMENTS, TO SOUTH SIDE TRUST COMPANY, TRUSTEE, OF PITTSBURGH, PENNSYLVANIA, A CORPORATION OF PENNSYLVANIA.

NAIL-FEEDING MECHANISM.

1,137,316.

Specification of Letters Patent. Patented Apr. 27, 1915.

Application filed November 25, 1910. Serial No. 594,073.

To all whom it may concern:

Be it known that I, HENRY C. HERR, a citizen of the United States of America, residing at Detroit, in the county of Wayne 5 and State of Michigan, have invented certain new and useful Improvements in Nail-Feeding Mechanism, of which the following is a specification, reference being had therein to the accompanying drawings.

10 The invention relates to nail feeding mechanism, and consists in the novel construction of means for sorting and delivering nails, applicable to various forms of nailing machines as hereinafter set forth.

15 In the drawings, Figure 1 is a vertical longitudinal section through the mechanism; Fig. 2 is a plan view thereof; Fig. 3 is a sectional perspective view; Fig. 4 is a sectional plan view of the nail extracting mechanism; Fig. 5 is a cross section on line $x-x$ Fig. 1; Fig. 6 is a plan view of a portion of the slides; Fig. 7 is an enlarged portion of Fig. 1 showing the operation; and Fig. 8 is a section on line 25 $y-y$ Fig. 1.

My improved machine comprises generally, mechanism for sorting an irregular mass of nails and arranging the same in parallelism, further, means for feeding the parallelly arranged nails and delivering the same, and further, means associated with the feeding and delivery mechanism for reversing the nails where such an operation is necessary for the proper delivery to the 35 nailing machine.

A suitable supporting frame upon which is mounted a hopper or receptacle B for the nails which is arranged with its bottom C in inclined position. This bottom 40 C is formed with a series of inverted V-shaped ribs D thereon arranged in parallelism and extending in the direction of inclination of the bottom. Between these ribs are formed V-shaped grooves D' which at the bottom are of just sufficient width to 45 freely receive the body of the nail but too narrow for the entrance of the head.

E are inverted V-shaped slides preferably formed of sheet metal and feeding over the 50 ribs D and slideable longitudinal thereon. These slides are attached to a cross-head F which is reciprocated by suitable means such as the crank disks G upon the rotary shaft H, and the pitman connection I between

said cranks and the cross-head F. The wall 55 J of the receptacle B which is on the lower side thereof extends into proximity to the apices of the V-shaped ribs and is then undercut at J' to form a recess of a length preferably equal at least to the length of 60 the nail. At the end of this recess are dependent V-shaped lugs J² which fill the space between the ribs D with only sufficient clearance to permit the free sliding of the members E. The apices of these lugs J² 65 are however, cut-away at J³ to form a channel of sufficient size for the passage of a nail and its head out from the receptacle.

Extending downward from the receptacle B are inclined nail guides preferably formed 70 by slots K in a bed member K' forming an extension of the bottom C. The slots K are in alignment with the grooves D' in the bottom C of the receptacle and are of width to permit the passage of the body of the 75 nail therethrough but preventing the passage of the head, these slots extending beneath the lugs J² which latter extend beneath the wall J of the receptacle, as shown in Fig. 1.

L are stops preferably formed by a plate 80 secured to the lower end of the lugs J² and depending into line with the channels J³ in the path of the nail heads. The stops are so positioned that the distance between the same and the upper ends of the guide 85 slots K is greater than the length of a nail, the arrangement being such that a nail passing head first through the channel J³ upon striking the stop L will be thrown downward, the body passing through the slot K 90 while the head remains in engagement with the guide. When in this position the nail is free to slide downward along the guide being suspended by their heads.

At the lower end of the bed K is arranged 95 a delivery mechanism by which a single nail from each of the slots K may be extracted therefrom, all of said nails being simultaneously delivered. This mechanism comprises a reciprocatory bar M movable transversely of the guides at the lower end thereof and having notches M' which normally register with the slots K. Above the bed K' is a cross-bar N which is slotted at N' 100 for the passage of the heads of the nails, 105 and is also recessed at N² adjacent to the lower end of the slot, the recess having an inclined cam face N³ at one edge thereof.

The end of the bed plate K' is also notched or recessed at K² in registration with the recess N². By reason of this construction whenever the notches M' in the bar M register with the slots K the body of the nail in the slot will enter said notch and will thus be freed from the guide. When the bar M is moved laterally the nail will be carried still in engagement with the notch, while the head will pass into the recess N², here the cam face N³ forces the nail out of engagement with the notch M' permitting it to fall through the recess K² which is of sufficient size for the passage of the head.

With the construction as thus far described in operation the nails are placed in the receptacle B in an irregular mass resting upon the grooved bottom C; here the reciprocatory movement of the slides E will cause the shifting of the lowermost nails by frictional contact therewith tending to straighten them out to arrange them in parallelism and this tendency is increased by the action of gravity and the inclined face of the ribs D. Thus the grooves D' will be gradually filled with parallelly arranged nails which however, will be irregular as to the arrangement of the heads, some being arranged with their heads downward and others with their heads upward. The lowermost nail in the groove D' will rest with its head against the sides of the slides E while the body is free to drop between said slides onto the bottom of the groove D'. In this position if the nail is arranged with its head downward it will be frictionally carried with the downward movement of the slides E and will be carried into the channel J³ which is of sufficient size for the passage of the head, finally passing out through said channel and dropping into engagement with the groove K. If on the other hand the nail is arranged with the head at the upper end it must be prevented from entering the channel J³ as there would be danger of more than one nail entering said channel at the same time and thereby producing a jam. For this purpose a stop O is placed in the groove D' and preferably a plurality of said stops are so arranged and will engage with the point of any nails which extend point downward but will not engage the heads of the nails, since the stops are positioned in the bottom of the groove and the latter at their base are of lesser width than the head of the nail. Thus further downward movement of the nail will be arrested, and as soon as the slides E in their downward movement pass from beneath the head it will drop to be in the path of the end of said slides on the return movement which will carry the nail backward.

It will be evident from the description just given that the nails which are arranged with heads downward, upon reaching the

bottom of the groove D' will be permitted to feed outward through the channels J³, but the nails reversely arranged with heads upward will be moved backward by the slides, furnishing space for other nails from above to take their places. This will bring about a slow rotation of the mass of nails within the receptacle and in the end those nails which were originally arranged points downward will be reversed and will drop between the slides with heads downward. To prevent danger of a series of nails arranging themselves end-to-end in the groove D' and obstructing upward movement of the slides, the ribs D are cut-away at the upper end of the receptacle leaving a space D³ which is more than the length of one nail. In this space nails which are in alinement with a series of nails in the groove D' will be permitted to move angularly and thus will not obstruct the slides.

Whenever a nail arranged head downward is drawn outward by the slides E through the channel J³ it will continue to move until arrested by the stop L. The lower ends of the slides E adjacent to the cross-head F are slightly cut-away at E' providing a clearance space through which the head of the nail can pass, and beneath this cut-away portion is a depression K³ in the bed K'. Thus in the upward movement of the slide the nail will remain in contact with the stop L until the cut-away portion E' permits the head to drop into the depression K³, whereupon it is freed from the stop L and can slide downward through the groove K. As the nails accumulate in this groove K they will mount higher therein until finally the nail last deposited will remain beneath the cut-away portion E' of the slots and will prevent the nail next drawn downward by the slides from dropping through said cut-away portion. This will temporarily stop the feeding of nails through the channel J³ until the extraction of nails at the lower end of the guide by the reciprocatory bar M and the feeding of the series downward through the slots K will again provide space at the upper end of said slot for the reception of another nail. The depression K³ in the bed K' may be formed as a channel of greater width than the slot K and sufficient to receive the head of the nail.

The nails when released by the reciprocatory bar M will fall point downward. For certain machines it is desirable to feed the nails head downward and also to accurately time the release so that all of the nails simultaneously extracted by the bar M will be dropped at the same instance. For this purpose the machines may be provided with the reversing mechanism comprising a rotary bar P having pockets P' therein which register with the nails released by the bar M. Below the reversible member P are ar-

ranged feed conduits Q and extending from these conduits adjacent to the path of movement of said bar is a segmental guide R.

S is a gate or slide which is normally in a position to cover the conduits Q.

T are springs for retracting said gate which are sleeved upon guides T' and abut against supporting bearings T².

U is a finger or lug projecting from the slide or gate S, and V is a cam coöperating with this lug or finger to move the gate to its normal position against the tension of the spring T. The cam V has a notch V' in its periphery which when in registration with the lug U will permit it to move backward under the actuation of the spring T thereby withdrawing the slide or gate.

With the construction just described the nails released by the reciprocatory bar M are first deposited in the pockets P' of the reversible member P, and as the latter is rotated are carried around, being held from displacement by the segmental guide R until the heads of the nails rest upon the gate 25 or slide S in registration with the feed conduits Q. When in this position the rotation of the cam V will register the notch V' with the lug or finger U and the action of the spring T will instantaneously withdraw 30 the gate, dropping all of the nails simultaneously head downward into their respective conduits.

For driving the mechanism employed in moving the slides E operating the extractor bar M and the reversing bar P, suitable means is provided which as shown consists of the shaft W on which the cams V are directly mounted. From this shaft the shaft H is driven through the medium of 40 intermeshing gears W' and W², the latter being formed on the periphery of the cranks G. The member P is rotated from the shaft W by the intermeshing gear wheels X and X', and a cam Y carried by the gear wheel 45 X' engaging an anti-friction roll Y' on the bar M serves to actuate said bar in one direction. The return movement of the bar M is effected by a spring Z.

What I claim as my invention is:

50 1. In a nail feeding machine, the combination with a receptacle for an irregular mass of nails, means operating within said receptacle for arranging the nails in parallelism, means permitting the successive passing out of said parallelly arranged nails from the receptacle when arranged head foremost, and means for successively withdrawing from said parallelly arranged nails, those which are point foremost.

60 2. In a nail feeding machine, the combination with a receptacle for an irregular mass of nails, of a reciprocating member within said receptacle for effecting a parallel arrangement of the lowermost nails 65 therein, means permitting the successive ex-

traction from said receptacle of those of the parallelly arranged nails which are head foremost and for withdrawing from said parallelly arranged nails those that are point foremost.

70 3. In a nail feeding machine the combination with a receptacle for an irregular mass of nails, of means operating within said receptacle for arranging the lowermost nails thereof in parallelism, and selective means operating upon said parallelly arranged nails for successively feeding those having their heads arranged in one direction out from the receptacle and for returning to the irregular mass those of the parallelly arranged nails those whose heads are in the opposite direction.

75 4. In a nail feeding machine the combination with a receptacle for an irregular mass of nails having a grooved and inclined bottom, of a slide covering a side of the groove, means for reciprocating said slide, and a channel registering with the bottom of the groove through which nails are successively fed by said slide.

80 5. In a nail feeding machine, the combination with a receptacle for an irregular mass of nails, of a grooved and inclined bottom for said receptacle, a slide covering the sides of said groove adapted to support the head of the nail but cut-away to permit the body of the nail to rest upon the inclined bottom, means for reciprocating said slide, and a channel in registration with the bottom of said groove through which the nails 90 are successively extracted.

85 6. In a nail feeding machine, the combination with a receptacle for an irregular mass of nails, of a bottom for said receptacle having a V-shaped groove therein inclined longitudinally, a slide covering the angling sides of said groove cut-away at the bottom to permit the passage of the body of a nail therebetween but affording support for the head of the nail, a wall for the lower side of said receptacle apertured for the passage of said slide therethrough, and a depending portion on said wall between the angling sides of said slide for restricting said aperture to a size for the passage of 100 one nail and its head therethrough.

105 7. In a nail feeding machine, the combination with a receptacle for an irregular mass of nails, of a bottom for said receptacle having a V-shaped groove therein inclined longitudinally and having at its bottom a slide or channel of just sufficient width to receive the body of a nail, a slide movable longitudinally of said groove and covering the sides thereof but cut-away at the bottom in registration with said narrow slot, a wall for the lower side of said receptacle through which said slide passes having a channel therethrough at the bottom of the groove of just sufficient size for 110 115 120 125 130

the passage of one nail and its head, and means in said narrow slot for intercepting the downward passage of a nail in said groove when moving point foremost.

8. In a nail feeding machine, the combination of a receptacle for an irregular mass of nails having a V-shaped grooved bottom inclined longitudinally, a slide covering the inclined sides of said groove and supporting the head of a nail in the bottom of said groove but cut-away to permit the body of the nail to pass therebetween, said slides extending outward through the lower side wall of the receptacle, means for reciprocating said slide to arrange the nails in parallelism in the groove, a channel in the lower side wall of the receptacle through which a single nail and its head can pass, and a stop on the stationary bottom of said groove for arresting point foremost nails carried on said slides.

9. In a nail feeding machine, the combination with a receptacle for an irregular mass of nails, of a bottom for said receptacle having a series of parallel V-shaped grooves therein inclined longitudinally with inverted V-shaped ribs therebetween, inverted V-shaped slides covering said ribs and the sides of said grooves but cut-away to expose the stationary bottom of the groove a sufficient width for the body of a nail, a wall for the lower side of said receptacle through which said slides pass cut-away to form channels at the bottom of the grooves sufficient for the passage of a single nail and its head, and means for reciprocating said slides to alternately cover and uncover the sides of said grooves to an extent more than the length of a nail.

40 10. In a nail feeding machine, the combination with a receptacle for an irregular mass of nails, of a bottom for said receptacle having a V-shaped groove therein inclined longitudinally, a slide covering the sides of said groove but cut-away at the bottom for the passage of the body of a nail therebetween, a wall for the lower side of said receptacle through which said slide passes cut-away to form a channel registering with the lower portion of said groove sufficient for the passage of a nail and its head, and means for reciprocating said slide to alternately cover and uncover the sides of said groove and movable to an extent more than 55 the length of one nail.

11. In a nail feeding machine, the combination with a receptacle for an irregular mass of nails, of a bottom for said receptacle having a series of parallel V-shaped grooves therein inclined longitudinally, inverted V-shaped ribs between adjacent grooves cut-away at its upper end, an inverted V-shaped slide covering said rib and the sides of the adjacent grooves but 60 cut-away to expose the bottoms of said

grooves, and a lower side wall for said receptacle through which said slide passes providing channels in registration with said grooves sufficient for the passage of a single nail and its head therethrough, and 70 means for reciprocating said slide.

12. In a nail feeding machine, the combination with a receptacle for an irregular mass of nails, of a bottom for said receptacle having parallel V-shaped grooves therein 75 inclined longitudinally, and an inverted V-shaped rib therebetween, an inverted V-shaped slide covering said rib but exposing the bottoms of said grooves, a lower side wall for said receptacle through which said 80 slide passes having dependent lugs on opposite sides thereof extending into said grooves but cut-away for the passage of a single nail and its head, and means for reciprocating said slide.

13. In a nail feeding machine, the combination with a receptacle for an irregular mass of nails, of a bottom for said receptacle having a V-shaped groove therein inclined longitudinally, a reciprocating slide covering the sides of said groove but cut-away at the bottom, a lower side wall for said receptacle through which said slide passes providing a channel in registration with the bottom of said groove for the passage of a 95 single nail and its head, a stop at the outer end of said channel for engaging the head of the nail, and a guide slotted for the drop of the body of the nail therethrough when the head thereof is arrested by said stop. 100

14. In a nail feeding machine, the combination with a receptacle for an irregular mass of nails, of an inclined reciprocating slide passing into and out from said receptacle said slide having V-shaped sides for 105 supporting the head of a nail cut-away at the bottom for the passage of the body of the nail therethrough, a channel in the wall of said receptacle through which a single nail and its head can pass while the latter is 110 supported on said slide, a guide for the nail outside said receptacle in alinement with said channel slotted for the passage of the body of the nail, and a stop for the head of the nail above said guide spaced from the 115 upper end of said slot equal to the length of a nail whereby said nail will be turned into a substantially vertical position, said guide having a depression into which the head of the nail drops to disengage from said slot 120 and provide clearance for the head of a succeeding nail.

15. In a nail feeding machine, the combination with a receptacle for an irregular mass of nails, of an inclined bed forming the 125 bottom of said receptacle, and a nail guide extending beyond the same, inverted V-shaped ribs on said bed within the receptacle forming a series of parallel downwardly inclined V-shaped grooves therebetween, in- 130

- verted V-shaped slides covering said ribs and passing into and out from said receptacle, said slides providing space therebetween at the bottoms of said grooves for the body 5 of a nail but supporting the head thereof, the wall of said receptacle having channels through which said slides pass registering with the bottom portions of said grooves and providing passage for the head of a nail 10 therethrough, and said bed having slots beyond said receptacle in registration with said channels and of a width for the passage of the body of a nail, and stops for the heads of the nails spaced a predetermined distance 15 from the upper ends of said slots.
16. In a nail feeding machine, the combination with a receptacle having a channel through which alined nails are successively fed, of an inclined guide in registration with 20 said channel slotted for the passage of the body of a nail but affording support for the head, and a stop spaced a predetermined distance from the end of said slot and adapted to engage the nail head.
- 25 17. In a nail feeding machine, the combination with a nail receptacle having a channel for the passage of a nail and its head out therefrom, of a slide for carrying the nail out through said channel, said slide being slotted for the passage of the body of a 30 nail therethrough and at its forward end being cut-away for the passage of the head of the nail for the purpose described.
- 35 18. In a nail feeding machine the combination with a guide in which a series of nails are suspended by their heads, of a member reciprocating transversely of the end of said guide for receiving and supporting by the head, a single nail, and a cam engaging the 40 nail while carried by said reciprocating member for disengaging the head from its support.
- 45 19. In a nail feeding machine, the combination with an inclined guide for suspending a series of nails by their heads and feeding the same by gravity, of a member reciprocated transversely of the lower end of said guide for receiving therefrom a single nail and supporting the same by its head, 50 and a stationary cam for engaging the head of said nail during the reciprocation of said member and disengaging it from its support.
- 55 20. In a nail feeding machine, the combination with a receptacle for an irregular mass of nails, of reciprocating means within said receptacle for arranging the nails in alinement, a channel through which nails may be successively fed head foremost from the receptacle, a stop for intercepting the point foremost nails before engagement of 60 the same with said channel, and means for carrying said arrested nails backward to clear the path for succeeding nails.
21. In a nail feeding mechanism, the combination with a receptacle for an irregular mass of nails having a grooved and inclined bottom, of a slide covering a side of the groove, means for reciprocating said slide, a channel registering with the lower end of the groove through which the nails are successively fed by said slide, and a guard in 65 said receptacle above the mouth of said channel for preventing a wedge of nails therein.
22. In a nail feeding machine, the combination with a receptacle for an irregular mass of nails, means operating in the receptacle for feeding the lowermost nails from within the receptacle to without the same head foremost, and means within the receptacle for preventing the feeding of the nails 70 having their points foremost.
23. In a nail feeding machine, the combination with a receptacle for an irregular mass of nails, means reciprocating across the bottom of the receptacle for feeding nails to without the receptacle, means coöperating with said reciprocatory means, permitting the feeding of the nails arranged head foremost, and means preventing the feeding of 80 nails arranged point foremost.
24. In a nail feeding machine, the combination with a receptacle for an irregular mass of nails, of a grooved and inclined bottom for said receptacle, a channel in registration with the bottom of said groove through which the nails therein are successively extracted, and means for preventing the clogging of the nails in said channel. 85
25. In a nail feeding machine, the combination with a receptacle for an irregular mass of nails, means projecting through one wall of said receptacle for feeding nails from within the receptacle to without the same head foremost, said wall having an under-cut portion, for the purpose described. 90

In testimony whereof I affix my signature in presence of two witnesses.
